UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

ELECTRICAL COIL.

1,424,726.

Specification of Letters Patent. Patented Aug. 1, 1922.

Application filed December 22, 1920. Serial No. 432,521.

To all whom it may concern:

Be it known that I, KENNETH S. JOHNSON, a citizen of the United States, residing at Jersey City, in the county of Hudson, State of New Jersey, have invented certain new and useful Improvements in Electrical Coils, of which the following is a full, clear, concise, and exact description.

This invention relates to electrical coils, 10 and in particular to that class of coils used in telephone substation circuits.

An object of this invention is to provide an electrical coil in which is combined effectively the usual transformer and the balancing network in an anti-side tone telephone circuit. Another object is to reduce the 15 number of parts required in the subscriber's set.

In general the invention consists in winding on the same magnetic core two closely coupled windings answering the purpose of the transformer, and a third winding somewhat loosely coupled to each of the transformer windings. This third winding performs a double function, acting as a transformer winding and as a balancing network.

It is well known that in order to properly balance any anti-side tone substation circuit so that there will be no side tone in 20 the receiver of the transmitting station when transmitting, it is necessary for the impedance of that portion of the circuit which provides the balancing network to have effectively the same phase angle as that of the line to which the set is to be connected. In connection with common battery anti-side tone sets, it has been found that the phase angle of the average line (at 800 to 1000 cycles) to which such sets are connected, is very close to zero, and consequently the balancing network in such circuits is essentially a non-inductive resistance. Examples of such circuits are shown in a general way in Patent No. 1,254,474 of 25 January 22, 1918, to G. A. Campbell, and more specifically in my patent 1,396,760 of November 15, 1921.

Cases frequently arise, however, where the impedance of the line to which the set is connected has a highly positive phase angle, for example, where the impedance has considerable inductive reactance. This condition frequently occurs when one subscriber's set is directly connected by an electrically 30 short line to another subscriber's set. Under

these conditions since the balancing network of any anti-side tone set must have the same phase angle as that of the line, it is necessary to have the balancing network consist essentially of a resistance and an inductance, 60 or what is effectively a retardation coil. The use of a retardation coil in addition to the transformer ordinarily required in anti-side tone substation circuits becomes relatively expensive and this invention provides one 65 electrical coil which will fulfill the requirements of both.

In the drawing Fig. 1 represents the coil shown part in section. Fig. 2 shows diagrammatically the windings on the coil. 70

Referring to Fig. 1, core 1 is composed of magnetic material, preferably silicon steel strips or iron wires, and covering said core is a suitable wrapper 2 of insulating material. Ends 6 and 7 of insulating material 75 provided at the extremities of the core with wrapper 2, form a spool. Between ends 6 and 7 and supported on said spool is partition 8 of insulating material so located that the winding space between it and end 6 is 80 symmetrical with respect to the ends of the core. Wound concentrically in said space are windings 3 and 4. Wound partly over windings 3 and 4 and partly in the space between partition 8 and end 7 is winding 5 which may, if desired, be two separate windings in series.

The windings 3 and 4 are closely coupled with respect to each other, and winding 5 is somewhat loosely coupled to these. By 90 varying the amount of the winding 5 wound over 3 and 4, the degree of coupling may be varied to suit different circuit requirements. It will be seen that by winding 5 completely over 3 and 4, a very closely coupled relation 95 will be obtained, and on the other hand by winding 5 completely in the space between partition 8 and end 7, a somewhat loose coupling will result. The latter relation gives a coefficient of coupling of only approximately 50 percent between windings 3 and 5; and 4 and 5, the remaining inductance of winding 5 acting as a retardation coil in series with the coupled portion of the winding. The result of such a relation may be illustrated by the following practical example. Suppose winding 5 has a direct current resistance of 44 ohms and self-inductance of .027 henry. The portion of this inductance 100 which is coupled with the other winding, 110

however, is only about .007 henry, leaving approximately .020 henry, acting as a retardation coil. In other words, this coil would be essentially identical to another coil 5 in which winding 5 is wound entirely over windings 3 and 4, but wound with such a number of turns as to give it a self-inductance of .007 henry plus a separate impedance coil inserted in series with the winding 10 5 (entirely over 3 and 4), and having an inductance of .020 henry, the total resistance of the impedance coil and winding 5 (entirely over 3 and 4) being the same as that of winding 5 alone distributed as shown in 15 Fig. 1.

In the case just described the phase angle of the balancing impedance (which at 796.4 cycles was $44+J.020 \times 5000 = 44+J.100 = 109 / 66.2^\circ$) was 66° , which is somewhat 20 higher than that usually needed to properly balance the line impedance. In applying this to electrically short lines such as in apartment house telephone systems, it has been found that the phase angle should be 25 slightly less than 45° . This is accomplished by winding 5 partly distributed over windings 3 and 4 as shown in Fig. 1.

It will, therefore, be seen that any degree of coupling may be obtained between winding 30 5 and windings 3 and 4, or any desired phase angle may be given the net-work provided the phase angle is not greater than that which may be obtained by winding the entire balancing winding in the space between partition 8 and end 7.

What is claimed is:

1. An electrical coil comprising a mag-

netic core, a plurality of windings wound in concentric relation thereon, said core projecting equidistant from each end of said windings, a single winding wound on one projection of said core, said single winding loosely coupled to said concentric windings. 40

2. An electrical coil, a magnetic core, a plurality of concentric windings thereon, 45 said core projecting beyond said windings, an additional winding distributed by winding part concentric with aforesaid concentric windings and part adjacent thereto on said projecting core to give a predetermined coupling between said concentric windings and said additional winding. 50

3. An electrical coil comprising a magnetic core, a coil having primary, secondary and tertiary windings wound in concentric relation thereon, said core projecting equidistant beyond each end of said concentric windings, a single winding on one projection of said core, said single winding in series with and inductively aiding said tertiary winding, and loosely coupled to said primary and said secondary windings. 55 60

4. In a telephone circuit, a telephone line having a definite phase angle, a telephone set connected thereto, said telephone set containing an electrical coil, said coil comprising a transformer having a projecting core, an additional winding distributed over said transformer in such a manner as will give the same phase angle as that of said line. 70

In witness whereof, I hereunto subscribe my name this 17th day of December A. D., 1920.

KENNETH S. JOHNSON.
